CLAIM

The ornamental design for a folding hook, as shown and described.

DESCRIPTION

FIG. 1 is a left side elevation view of a folding hook showing my new design in the open position, the opposite side being a mirror image.

FIG. 2 is a front elevation view of the folding hook shown in the open position.

FIG. 3 is a rear elevation view of the folding hook shown in the open position.

FIG. 4 is a top plan view of the folding hook shown in the open position.

FIG. 5 is a bottom plan view of the folding hook shown in the open position.

FIG. 6 is a left side elevation view of the folding hook shown in the closed position, the opposite side being a mirror image.

FIG. 7 is a left-front perspective view of the folding hook shown in the closed position.

FIG. 8 is a front elevation view of the folding hook shown in the closed position.

FIG. 9 is a rear elevation view of the folding hook shown in the closed position.

FIG. 10 is a top plan view of the folding hook shown in the closed position; and,

FIG. 11 is a bottom plan view of the folding hook shown in the closed position.
